UNITED STATES PATENT OFFICE.

ADOLF SCHWIEGER, OF HANOVER, GERMANY, ASSIGNOR TO AUGUST BAUROSE, OF GODESBERG, PRUSSIA, GERMANY.

COLLAR-BUTTON.

No. 807,689.

Specification of Letters Patent.

Patented Dec. 19, 1905.

Application filed January 12, 1905. Serial No. 240,837.

To all whom it may concern:

Be it known that I, ADOLF SCHWIEGER, a subject of the German Emperor, residing at Hanover, in the Kingdom of Prussia and Empire of Germany, have invented a new and useful Improvement in Collar-Buttons, of which the following is a specification.

My invention relates to improvements in that class of collar-buttons in which there is a gripping device; and the object of my invention is to hold the necktie securely and prevent it from pulling forward, riding up in front, or sliding around on the neck. I attain these objects by the mechanism illustrated in the accompanying drawing, which shows a central section of the improved button on an enlarged scale.

The collar-button is of the usual exterior shape, size, and general appearance and comprises stem *a*, integral with the head *d*, and base *f*. The base *f* is hollow and has an inwardly-turned flange *f'* to retain the plate *g*, which closes the bottom end of the base. Through the stem *a* and head *d* there extends a central bore *h*, open at each end and laterally enlarged at the head, as at *h'*, to house the claws on the neckwear-retainer next to be described. Through the bore *h* there extends a looped needle *b*, formed of two parallel wires, the outer ends of which are bent outward from one another and are curved inward to form two claws *e e*. The spring *c* tends to keep the needle and its claws *e e* always drawn inward, so that the claw or claws *e e* do not while in their normal position project beyond the head, but lie in the recess *h'*.

The spring *c* engages the looped end of the needle *b*.

By pressing on the plate *g*, forming the lower part of the base of the button, the plate *g* is brought into the position shown in dotted lines, and the needle or loop *b* is moved axially outward and its claws *e e* projected beyond the head *h*, whereupon, owing to the resilient nature of the needle, they spread laterally apart, as shown in dotted lines, to engage the fabric of the neckwear. Relaxing the pressure on the plate *g* the needle *b* is drawn inward and the claws *e e* are drawn together and inward, engaging the fabric of the neckwear. This latter is held in place until upward pressure is again voluntarily exerted by the wearer upon the plate *g*, when the projection of the needle *b* and the claws *e e* permits of releasing the neckwear from the hold of the latter and its readjustment or removal.

What I claim as my invention, and desire to secure by Letters Patent, is as follows:

In a button, the combination of a headed stem having an axial bore, laterally enlarged within the head, with a looped needle terminating in a pair of self-separating claws adapted to be compressed within the enlarged bore, a spring for drawing the needle inward into the bore and means for counteracting the spring-pressure and projecting the needle-claws at will.

Signed this 2d day of January, 1905.

ADOLF SCHWIEGER.
